(57) CLAIM

The ornamental design for a headwear, as shown and described.

DESCRIPTION

FIG. 1 is a Bottom Perspective View of a headwear according to my new design;

FIG. 2 is another Bottom Perspective View thereof;

FIG. 3 is a Rear View thereof;

FIG. 4 is a Side View thereof;

FIG. 5 is a Bottom Perspective View with environment associated with the claimed design; and,

FIG. 6 is another Bottom Perspective thereof.

The broken line outline of a hat in FIGS. 1-6 and the broken line outline of a hook in FIGS. 5 and 6 depict the environment associated with the claim and forms no part of the claimed design. The evenly dashed broken lines along the surfaces of the Headwear depict claimed stitching.
